CUTTING AND STAPLING DEVICE

Joseph T. Cooper, Alhambra, Calif.

Application January 4, 1943, Serial No. 471,263

4 Claims. (Cl. 1—47)

My invention relates to a cutting and stapling device and more particularly to such a device that operates automatically after being initially actuated by manual means.

An object of the present invention is to provide automatic means for severing corrugated nails from corrugated strip material and then driving such corrugated nails into materials.

Another object of the invention is to provide mechanism for automatically severing and driving corrugated nails by pneumatic pressure.

Still another object of the invention is to provide means for severing a corrugated nail from a strip of corrugated material and to provide means for preventing further feeding of the corrugated material until the severed portion has been driven from the machine.

Further objects are to provide such a device that can be operated in a vertical as well as a horizontal position and to provide such means that may be operated pneumatically, electrically or hydraulically.

My invention also has for its objects to provide such a device that is positive in operation, convenient in use, manually movable to and from a working position, economical of manufacture, relatively simple and of general superiority and serviceability.

The invention also comprises novel details of construction and novel combinations and arrangements of parts, which will more fully appear in the course of the following description. However, the drawings merely show and the following description merely describes two embodiments of the present invention, which are given by way of illustration or example only.

In the drawings, like reference characters designate similar parts in the several views.

Fig. 1 is a plan view of an embodiment of my invention.

Fig. 2 is an elevation, partly in section, of said embodiment.

Fig. 3 is an enlarged section taken on line 3—3 of Fig. 2.

Fig. 4 is an enlarged section taken on line 4—4 of Fig. 2.

Fig. 5 is an enlarged section taken on line 5—5 of Fig. 2.

Fig. 6 is an enlarged section taken on line 6—6 of Fig. 2.

Fig. 7 is a broken section taken on line 7—7 of Fig. 4.

Fig. 8 is a somewhat enlarged bottom view of the present invention taken on line 8—8 of Fig. 2.

Fig. 9 is a view similar to Fig. 8, but showing parts therein in different operative positions.

Fig. 10 is an elevation, partly in section, of a modified construction.

Referring more in detail to the drawings, the reference number 10 generally designates an elongated housing that is slotted, as shown at 12, for feeding corrugated strip material 13 to the device.

10 A follower member 14 slides longitudinally in the slot 12 and is urged forward by a spring-urged strap 15 that is wound under spring tension in a casing 16. The outer end of the strap 15 is hooked over a pin 17 on a lug 18 that is upstanding on the follower member 14. A bottom plate 19 closes the bottom portion of the slot 12. Screws 20 maintain the bottom plate 19 in position.

A bowed handle 21 is mounted between the 20 housing 10, and an upright cylinder 22 is disposed upon the housing. A knob 23 arranged on top of the cylinder 22 provides manual means to aid in handling the present tool.

An inlet opening 24 is tapped to receive a pressure supply conduit (not shown). An inlet passage 25 connects with the opening 24 and in turn connects with the interior of the cylinder 22 through the head 26 thereof. The head 26 also has a transverse passage 27 that connects

30 with the atmosphere at opposite sides of the head. A downward passage 28 connects the transverse passage 27 with the interior of the cylinder 22.

A bore 28 is disposed in the head 26 at right 35 angles to the passages 25, 27 and 28. A sliding valve 29 is arranged in the bore 28. The greatest diameter of the valve 29 closes the passages 25, 27 and 28. However, the valve 29 has reduced portions 30 and 31, which when opposite 40 these passages respectively, do not close same.

An extension spring 32 is inclosed in a hollow boss 33 projecting laterally from the head 26. A pin 34 anchors one end of the spring 32. The other end of said spring is pinned to valve 29.

45 The spring 32 tends to maintain the valve 29 in the position shown in Fig. 2. A solenoid 35 in a housing 36 is aligned with the valve 29, whereby such valve constitutes the core of the solenoid. Energization of the solenoid 35 draws the valve 50 to the right in Fig. 2, against the action of the spring 32. When the solenoid is turned off, the spring 32 returns the valve 29 to the position shown in Fig. 2. A button 37 on the handle 21 is connected to manually control a switch in the 55 circuit of the solenoid 35.

A piston 38 has a cup leather 39 mounted thereon to provide a substantially fluid tight contact with the inner wall of the cylinder 22. A coil spring 40 tends to hold the piston 38 in the upper position shown in Fig. 2. The piston 38 is arranged upon a cylindrical plunger 41, which operates in a cylindrical opening 42, axially aligned with and below the interior of the cylinder 22.

Mounted on the side of the plunger 41 is a driving rod 43 that is beveled on its lower face, as shown at 44. Arranged in the downward path of the driving rod 43 is a bevel faced end 74 of an L-shaped arm 45. A coil spring 46 tends to maintain the bevel faced end 74 in the path of the driving rod 43. A screw plug 47 closes the opening through which the coil spring 46 is placed in position. An offset link 48 is pivoted at 49 and pivotally connected to the arm 45 at 50. The link 48 has a nose 51 arranged to push a shearing block 52 transversely of the body 53. The shearing block 52 has a shoulder 54. A coil spring 55 is disposed between the shoulder 54 and a fixed portion of the body 53. The spring 55 tends to resist shearing action of the block 52 and to return such block to its pre-shearing position, as shown in Fig. 8. The position of the block 52 following shearing is shown in Fig. 9. The shearing edge of the block 52 is beveled, as shown at 56 in Fig. 6, to facilitate the shearing action.

An arm 57 pivoted at 58 within the body 53 is urged by a flat spring 59 to move the corrugated strip material 13 into alignment with a slot 60, which leads to the cylindrical bore 42.

After the shearing action by the block 52 takes place, the new end of the corrugated strip 13 is moved out of alignment with the slot 60, as shown in Fig. 9, whereby said new end of the strip 13 abuts against a face 61 in the body 53, leaving the sheared corrugated nail 62 in the path of the plunger 41. Thus the corrugated strip 13 cannot feed into the slot 60 while the block 52 is in effective position, and it will be noted that the plunger-operated connections actuating said block are such that the block is maintained in effective position during the nail driving operation following severance of a nail.

After the nail 62 has been driven out of the bore 42 by the plunger 41, and the link 48 returned to its original position following release of the control button 37 and return of the plunger 41, the block 52 is pushed back to the position shown in Fig. 8, and the arm 57 moves the strip 13 again into alignment with the slot 60. The plunger 41 has a projecting driving face 63 arranged parallel with the severed nail 62, whereby to drive the nail through slot 64 in the base plate and into the desired material.

The modification shown in Fig. 10 comprises a body member 80 having a head 81 upon which is mounted the knob 23. The handle 21 contains wiring 82. The button 37 manually operates a switch in the circuit containing the wiring 82.

A solenoid coil 83 in this form is arranged with the core 84 vertical. The plunger 85, similar in shape and function to the cylindrical plunger 41, is connected with the core 84 by means of an intermediate member 90 of non-magnetic material. The plunger 85, the member 90, and the core 84 have threaded endwise connections axially of each other. A driving rod 86 similar in shape and function to the driving rod 43, is arranged on the plunger 90, in the same manner that the driving rod 43, is arranged

on the plunger 41. A plate 87 is mounted upon the core 84 and provides an abutment against which a coil spring 88 engages. The other end of the spring 88 abuts against the relatively stationary solenoid 83. A spring-urged switch lever 91 is also connected in the circuit of the solenoid 83. The switch lever 91 is arranged between shoulders 92 and 93 in a groove 94 in the intermediate member 90. The shoulder 92 engages the lever 91 on the downward movement of the member 90, thereby moving the lever 91 to a circuit-opening position. Upon return movement of the member 90, under the influence of the spring 88, a spring 89 moves the lever 91 to a circuit-closing position. The lever 91 and the shoulder 92 are arranged to break the circuit of the solenoid 83 just prior to the time the plunger 85 reaches the point in the solenoid where the plunger is static. Thereby, the momentum of the plunger produces the driving action and not directly the energy in the solenoid.

In the operation of my device, a strip of corrugated material is fed into the slot 12 and arranged with a spring-urged follower 14 behind same. The spring-urged strap 15 maintains pressure behind the corrugated strip 13. By means of the knob 23 and handle 21 the tool is disposed with the slot 64 opposite the point into which it is desired to drive a corrugated nail. Thereupon the button 37 is pressed closing the circuit of the solenoid 35, which draws valve 29 into a position in which the reduced portion 31 of the valve is opposite the inlet 24. The pressure fluid thereupon flows through the passage 26 into the cylinder 22 above the cup leather therein.

Fluid pressure above the cup leather 39 causes the plunger 41 and the driving rod 43 to be driven downward, against the action of the spring 40. Before the plunger face 63 engages the corrugated material 13, the beveled face 44 of the driving rod 43 engages the correspondingly beveled face 74 of the L-shaped arm 45, thereby moving the link 48 inward within its recess 65, thus causing shearing by the block 52 of the end of the strip 13, to provide the severed, corrugated nail 62, as shown in Fig. 9.

Continued downward movement of the plunger 41 causes its driving face 63 to engage the top of the severed nail 62 and to drive the nail through the slot 64 and into the material, as desired.

Release of the button 37 breaks the circuit of the solenoid 35, whereby the spring 32 pulls the valve 29 to its exhausting position, shown in Fig. 2. In its exhausting position, the reduced portion 30 of the valve is aligned with the transverse passage 27 and the passage 28, whereby fluid pressure above the cup leather 29 will exhaust through the passage 28, past the reduced portion 30 of the valve, and through passage 27 to the atmosphere. When the valve 29 is in this exhausting position, it shuts off further supply of pressure fluid by reason of the larger diameter of the valve being in a closing position with respect to the passage 25.

When the fluid pressure is thus exhausted, the spring 40 returns the piston 38 to its original position; the spring 46 returns the arm 45 and the link 48 to their original positions; the spring 55 returns the shearing block 52 to its original position; and the spring 59 returns the arm 57 to its original position. The tool is now ready for the next cycle of operation.

In the operation of the modification shown in

Fig. 10, the circuit of the solenoid 83 is closed by pressing the button 37. Energization of the solenoid 83 causes it to attract its core member 84, which moves such member downward in Fig. 10, against the action of the spring 88. The switch lever 91 breaks the circuit of the solenoid just prior to the driving action of the plunger 85, permitting the latter's momentum to do the driving of the sheared nail 62.

The spring 88 returns the core and plunger to their original position. On their upward travel, the spring-urged lever 91 moves to a circuit-closing position. As long as the button 37 is depressed, the plunger and core continue to make downward and upward movements. When the button 37 is released, the core and plunger assume their uppermost positions.

While I have illustrated and described what I now regard as the preferred embodiments of my invention, the constructions are, of course, subject to modifications without departing from the spirit and scope of my invention. I, therefore, do not wish to restrict myself to the particular forms of construction illustrated and described, but desire to avail myself of all modifications that may fall within the scope of the appended claims.

Having thus described my invention, what I claim and desire to secure by Letters Patent is:

1. A machine for severing and driving corrugated nails, comprising a nail driving plunger, spring means for feeding corrugated strip material in the machine toward said plunger, means having an effective movement to sever a nail from said strip in advance of the plunger and at the same time deflect the adjacent portion of the strip out of feeding line, means actuated by the plunger prior to its engagement with the severed nail for shifting the severing means to effective position and maintaining the same in said position during completion of the nail driving operation, means for subsequently returning the plunger and severing means to inactive position, and means for shifting the uncut strip to feeding position after return of the severing means.

2. A machine for severing and driving corrugated nails, comprising a nail driving plunger, spring means for feeding corrugated strip material in the machine toward said plunger, a body member having a bore for the plunger and a feed slot opening into said bore to receive an end of the strip material, means for severing a nail within the bore and having an effective movement adjacent to said feed slot to simultaneously deflect the adjacent end of the strip material out of line with the feed slot, means actuated by the plunger prior to its engagement

with the severed nail for actuating the severing means and thereafter maintaining the same in strip deflecting position during the completion of the nail driving operation, manually controlled means for actuating the plunger, spring means to return the plunger and severing means following operation thereof, and spring-actuated means for returning the strip material into line with the feed slot after return of the severing means.

3. A machine for severing and driving corrugated nails, comprising shearing means including a movable shearing block, a yielding member opposed to the shearing block and arranged to receive corrugated strip material between the block and said member, the yielding member being arranged to permit the block to shear off a nail and move to an effective position for shifting at least a portion of the remaining strip material aside, whereby the material abuts against a relatively stationary part of the machine, to limit further feeding of the strip material, plunger means arranged to drive the severed nails from the machine, and means activated by the plunger and connected to operatively move and maintain the block in said effective position to hold the material in such abutting position during the nail-driving operation of the plunger means, the yielding member returning the material to a position to be fed to its next shearing position, upon return of the plunger and shearing block.

4. A machine for severing and driving corrugated nails, comprising plunger means arranged to drive the severed nails from the machine, spring-urged means for feeding corrugated strip material into the path of the plunger means and continuously exerting a feeding tension on said material, shearing means including a movable shearing block, a yielding member opposed to the shearing block and arranged to receive between the block and said member strip material fed by the spring-urged means, the yielding member being arranged to permit the block to shear off material fed into the path of the plunger means and to permit the block to move at least a portion of the remaining strip material aside, whereby the material temporarily cannot be fed into the path of the plunger means, means activated by the plunger means for effective movement of the shearing block and connected to maintain the block in its feed-restraining position during the nail-driving operation of the plunger means, the yielding member returning the material to a position to be fed to its next shearing position, upon return of the plunger and shearing block.

JOSEPH T. COOPER.
